REFRIGERATING SYSTEM

Siegfried Ruppricht, New York, N. Y.

Application March 18, 1931, Serial No. 523,471

12 Claims. (Cl. 62—4)

This invention relates to improvements in refrigerating systems and has for an object the provision of a plurality of refrigerating units operating from a condenser which is, in turn, refrigerated by any means such as a compression system, an absorption system, ice and salt, etc.

In multiple installations such as apartment houses, etc., it is very expensive to buy a complete unit such as is on the market today for each apartment. By the use of a main refrigerating unit and the system disclosed in this invention, the cost of such installations may be substantially reduced.

An auxiliary condenser made of a coil of pipe, preferably in the form of an inverted frustum of a cone, comprises the side wall of a chamber adapted to be refrigerated by the large unit referred to above. Gaseous refrigerant passing into this coil has its heat removed by the cold in the chamber, liquefies and settles into a receiver which is connected to the bottom of the condenser.

Liquid refrigerant is led from this receiver to a plurality of evaporators located in boxes 25 in the various apartments throughout the building, and a return pipe leads the gaseous refrigerant back to the auxiliary condenser, forming a separate closed system.

Suitable control means are provided for both 30 the main refrigerating unit and for the multiple auxiliary system.

The auxiliary condenser may be made in a variety of forms other than described above and the term "chamber" may be taken to mean any 35 conduit or vessel in heat exchange relation to the auxiliary condenser.

The auxiliary condenser and its allied evaporators contain no lubricants, absorbents or adsorbents which might tend to retard the heat 40 transfer by insulating the interiors of the pipes.

Another object of the invention is to superimpose a stream or spray of liquid refrigerant on the stream of gas passing through the auxiliary condenser in order to speed up the heat transfer and therefore accomplish faster liquefaction of the gas. This may be accomplished by any suitable means; for example, a centrifugal pump may be used in conjunction with a jet arrangement wherein the spray of liquid refrigerant 45 through the jet will cause the gaseous refrigerant to move therethrough at a greater rate of speed, thereby effecting faster condensation. This centrifugal pump may be driven by a motor and controlled by the pressure of the gaseous 50 refrigerant in the return pipe of the system.

Still another object of the invention is to provide a multiple auxiliary refrigerating system which will operate in a cycle or cycles independent in respect to the cycling of the main source of refrigeration. In cases where the relay condenser is refrigerated by a refrigerating machine the operation of the latter may be controlled manostatically or thermostatically, and it is sometimes preferable to have it make comparatively long runs, and sometimes preferable to have it 10 make comparatively short runs.

Another object of the invention is to have the liquid line surrounded by the gas line thereby effecting a heat exchange between the liquid and gaseous refrigerant and also insulating the liquid 15 refrigerant from the heat of the outside air.

Other objects will be apparent to those skilled in the art upon perusal of the specification and appended claims.

Referring to the drawing:—

Figure 1 is a diagrammatic view partly in section showing one embodiment of the invention, wherein the auxiliary condenser is located above the refrigerating units or evaporators;

Figure 2 is a diagrammatic view of a modification of the invention wherein a condenser is located below the cooling units or evaporators;

Figure 3 is a sectional view of an evaporator taken along the line 3—3 of Figure 2.

The relay condenser designated generally by 30 the numeral 10 consists of a vessel, the interior 11 of which serves as an evaporator for the main refrigerating system and refrigerant is supplied thereto from the receiver or condenser of the main refrigerating system via expansion valve 12 35 and the pipe 13. This pipe 13 terminates at a point near the bottom of the chamber 11, so that the refrigerant entering the chamber will agitate any refrigerant already in the chamber. The slanting walls 14 of the chamber are formed from 40 a coil of pipe wound in the form of a frustum of a cone. This coil serves as a condenser for the auxiliary system.

A bottom closure 15, preferably in the form of a dome and a top closure 16, also dome-shaped, are secured to the slanting walls 14 in any suitable manner to form the fluid-tight chamber 11. A suction pipe 17 is provided for removal of gaseous refrigerant from chamber 11.

To facilitate a circulation of liquid refrigerant 50 in the chamber 11, a conical shaped baffle 18 supported on the upper wall 16 by brackets 19 and 20 is provided. Suitable control means for the main refrigerating system may be provided.

A plurality of evaporators 21, 22 are connected 55

with the gas line 23, which extends to the jet 24 and connects thereto at the point indicated by the numeral 25. This jet is connected to the upper end of the coil which forms the wall 14. 5 The other end of this coil terminates in the receiver 26 and gaseous refrigerant passing from the evaporators 21 and/or 22 via pipe 23, condenses in the coils 14 and liquid refrigerant settles into receiver 26. This condensation is accelerated by superimposing on the gas stream a jet of liquid refrigerant which speeds up the passage of refrigerant through the coil 14 and at the same time overcomes friction of the gases against the walls of the pipe 23. This is accomplished in the following manner:—

Liquid refrigerant from the receiver 26 is supplied via the pipe 27 to a centrifugal pump 28. A motor 29, drives the centrifugal pump 28 and the liquid refrigerant which goes into the pump 20 via the pipe 27 is carried through the pipe 30 to the nozzle 31 of the jet 24 and the refrigerant leaving the jet in the form of a spray impels the gaseous refrigerant therethrough.

The pipe 30 also has connected thereto a pipe 25 32 which supplies liquid refrigerant to the evaporators 21 and 22. The operation of the motor 29 and its pump 28 is controlled by a sylphon bellows 33 which has its interior connected with the interior of the pipe 23. This sylphon 33 operates 30 a switch 34 which is connected to a source of power 35 and the motor 29 via the wires 36, 37, 38.

The arrangement shown in Figure 1 covers a system wherein the relay condenser is located at a point above the evaporators 21 and 22. In 35 many cases it is desirable to have the auxiliary condenser located at a point below the evaporators. Such an arrangement is shown in Figure 2 wherein the auxiliary condenser 18 has its interior chamber 11 connected via the pipe 17 to a compressor 39 of a refrigerating system. The 40 gas after being compressed passes via the pipe 40 into a condenser 41 and the gases liquefied therein settle into a receiver 42 and pass therefrom via the pipe 43, the expansion valve 12 and 45 the pipe 13 into the chamber 11. Any suitable method for driving and controlling the operation of the compressor may be provided.

A plurality of evaporators, 44, 45, 46 are provided and these are supplied with a liquid refrigerant from a tank 47 located at a point above the evaporators. The tank 47 is preferably surrounded by insulating material 48. A float valve 49 is provided in the tank 47 to keep a predetermined liquid level therein. Liquid is supplied 55 to the tank 47 via the pipe 50 in a manner which will hereinafter be described.

This pump 50 is surrounded by the suction pipe 51 which not only insulates it from the outside air but effects a heat exchange between gaseous refrigerant in the pipe 50 and liquid refrigerant in the pipe 51. This suction pipe is connected to the evaporators 44, 45, 46 by the pipes 52, 53 and 54, respectively. The pipe 55 connected to the pipe 51 has mounted thereon the 60 sylphon 33 which operates the switch 34, thereby controlling the operation of the motor 29 which drives the centrifugal pump 28 as above described.

The coil of pipe 56 is wound in heat exchange 70 relation to the wall 14 of the relay condenser and has therein a similar coil of pipe 57. Gaseous refrigerant from the pipe 55 is carried through the coil 56 and upon passing therethrough is led by the pipe 58 to the outer portion 75 of the jet 24. Liquid refrigerant is carried

from the receiver 26 via pipe 27 to centrifugal pump 28 and pipe 59 to the spray nozzle 31 of the jet 24. The pipe 59 has a branch connection 60 which connects to the coil 57 which is within the coil 56 and passes via the pipe 65, the pipe 5 50 and the float valve 49 to the receiver 47.

The tank 47 is connected to the suction pipe 50 by pipe 62 which contains a check valve 61. This check valve allows gas or vapor to pass from the tank 47 when liquid is passing in. 10

The evaporators 21, 22, Figure 1, are located in suitable insulated boxes and the system is charged with a suitable refrigerant.

The chamber 11 is refrigerated by any suitable method such as a high side unit as shown 15 at 39, 41, 42 in Figure 2, and gaseous refrigerant from the evaporators 21, 22 tending to seek the coldest part of the system flows via the pipe 23 into the auxiliary condenser 14 which forms the wall of the chamber 11. 20

The pressure in the pipe (and incidentally the evaporators 21, 22) causes the sylphon 33 to close the switch 34 and thereby complete the circuit between the motor 29 and the source of power 35. The pump 28 is driven by the motor 29 and takes 25 liquid refrigerant from the receiver 26 via the pipe 27 and, via the pipe 30, forces the liquid through the nozzle 31 of the jet 24.

The liquid leaving the nozzle 31 in a fine spray and at a high velocity mixes with and impels the 30 gaseous refrigerant into the condenser 14 at a high rate of speed thereby speeding up the rate of heat exchange between the cold chamber and the warmer gaseous refrigerant, which liquefies and settles into the receiver 26. 35

The evaporators 21 and 22 are provided with suitable expansion valves (not shown) and receive liquid refrigerant from the receiver 26 via the pipe 27, the pump body 28 and the pipe 32.

The operation of the system continues until 40 all evaporators connected thereto are reduced to the same temperature and the corresponding pressure in the return pipe 32 allows the sylphon 33 to open the switch whereupon the motor 29 and pump 28 cease to operate.

In this system only one control is necessary on a multiple installation as all of the evaporators in the system are reduced to a predetermined temperature and the rates of refrigeration of the various evaporators are inherently accelerated. 50 For example, when the system starts operating the warmest evaporator boils at a faster rate than the colder ones, and as the operation continues the rate of boiling gradually decreases as the temperature reduces and finally when they 55 will arrive at the predetermined temperature level, the operation ceases.

If a higher temperature is desired in one or more of evaporators of a system of this kind, a suitable automatic valve may be placed in the 60 return pipe of the evaporator in which the higher temperature is desired. Then when the temperature for which the automatic valve is set is reached, the valve closes and the temperature of that particular evaporator would not be further 65 reduced, while those not so equipped would be reduced to the desired low level.

The chamber 11 receives refrigerant from the main refrigerating machine via the expansion valve 12 and the pipe 13 leads the refrigerant to 70 a point near the bottom of the chamber from which it bubbles up through refrigerant already in the chamber and tends to increase the circulation of liquid in the chamber. This circulation is indicated by the arrows 63, and the slant of the 75

wall 14 tends to cause bubbles that form thereon to rise through the liquid instead of sliding along the surface.

In the system outlined in Figure 2, the operation is the same as described for Figure 1 except, that in this case the evaporators 44, 45, 46 are located above the level of the auxiliary condenser. An auxiliary receiver 47 is provided above the level of the evaporators, and a liquid line runs directly to this auxiliary receiver.

A second liquid line 64 supplies liquid refrigerant to the evaporators from the auxiliary receiver.

Gaseous refrigerant is led from the evaporators 44, 45, 46, via the pipe 51, the pipe 55, the coil 56, the pipe 58 and the jet 24 to the condenser 14.

The pipe 51 surrounds a part of the length of the liquid line 50 effecting a heat exchange between liquid and gaseous refrigerant and at the same time insulating the line 50 from the temperature of the outside air.

The coil 56 surrounds a portion 57 of the liquid line and is in heat exchange relation to the outside of the condenser coil 14.

The float valve 49 regulates the level of liquid in the auxiliary receiver 47 and the check valve 61 allows gas to escape into the return line 51 via the pipe 62 when the receiver 47 is being filled.

The check valve 61 is of sufficient weight or balance to prevent the loss of refrigeration by boiling in the receiver during the operation of the system.

The evaporators are each provided with a float valve having a float 69 mounted on a pivot pin 71 and so arranged when a predetermined level of liquid enters the evaporator, the needle valve 70 closes. A suction pipe 53 terminates in the evaporator above the liquid level. The liquid level is indicated by a dotted line 73.

A motor 67 driving the compressor 39 of the main refrigerating unit is electrically controlled by a pressurestat 68. The operation of the pressurestat is controlled by means of a small tube 72 which is connected to the crankcase of the compressor (which is of the same pressure as that of the low side 10). As such controls are well known in the art, the operation thereof is not explained in detail. However, this control supplies the motor 67 with current when the pressure in the low side 10 reaches a predetermined high thereby operating the compressor 39. When the pressure in the low side reaches a predetermined low pressure, the control 68 cuts the current off from the motor 67 and the compressor 39 ceases to operate.

I claim:

1. In an auxiliary refrigerating system, a main refrigerated chamber, an auxiliary condenser in heat exchange relation to said chamber, a receiver associated with said condenser, an evaporator adapted to receive liquid refrigerant from said receiver, a return pipe between said evaporator and the condenser, and means responsive to pressure in said return pipe for admixing cold liquid refrigerant with the gaseous refrigerant entering said condenser, thereby accelerating heat transfer between said evaporator and said chamber.

2. In an auxiliary refrigerating system, a main refrigerated chamber, an auxiliary condenser in heat exchange relation to said chamber, a receiver associated with said condenser, an evaporator adapted to receive liquid refrigerant from

said receiver, a return pipe between said evaporator and the condenser, and means responsive to pressure in the return pipe and including a jet pump for saturating gaseous refrigerant with cold liquid refrigerant and accelerating the flow of the same through said condenser.

3. In an auxiliary refrigerating system, a main refrigerated chamber, an auxiliary condenser in heat exchange relation to said chamber, a receiver associated with said condenser, an evaporator adapted to receive liquid refrigerant from said receiver, a return pipe between said evaporator and the condenser whereby gaseous refrigerant may flow from said evaporator to said condenser, means including a jet for accelerating the flow of refrigerant through said condenser, and means actuated by pressure in said return pipe for directly controlling the operating of said first means, thereby indirectly controlling the temperature of said evaporator.

4. In an auxiliary refrigerating system, a main refrigerated chamber, an auxiliary condenser forming a part of the walls of said chamber, a receiver associated with said condenser, an evaporator adapted to receive liquid refrigerant from said receiver, a return pipe for leading gaseous refrigerant from said evaporator to the condenser, a pump adapted to force cold liquid refrigerant through a nozzle of a jet injector and thereby increase the rate of heat transfer between refrigerant passing into said condenser and said chamber, a motor for driving said pump, and means actuated by pressure in said return pipe for controlling the operation of said motor.

5. In a refrigerating system, a main refrigerating machine including a cooling unit, a control therefor, an auxiliary condenser comprising a coil forming at least a portion of a wall of said cooling unit, a receiver for receiving liquid refrigerant from said condenser, a plurality of evaporators operatively connected to said receiver, an individual expansion valve for each of said evaporators, a return pipe for leading gaseous refrigerant from said condenser to said evaporators, means for increasing the rate of heat transmission through the wall of said condenser, and a control for said means adapted to operate independent of the operation of said first control.

6. In a refrigerating system, a main refrigerating machine including a cooling unit, a control therefor, an auxiliary condenser in heat exchange relation to said cooling unit, a receiver for receiving liquid refrigerant from said condenser, a plurality of evaporators operatively connected to said receiver, an individual expansion valve for each of said evaporators, a return pipe for leading gaseous refrigerant from the evaporators to said condensers, a jet pump in the return line adjacent the condenser, a pump in the connection between the receiver and the evaporators and arranged to force liquid refrigerant from said receiver through a nozzle in said jet and thereby increase the speed of refrigerant in the condenser, and a control for the operation of said pump adapted to operate independently in respect to the operation of said first control.

7. In a refrigerating system, a main refrigerating machine including a cooling unit, a control therefor, an auxiliary condenser in heat exchange relation to said cooling unit, a receiver for receiving liquid refrigerant from said condenser, a plurality of evaporators operatively connected to said receiver, an individual expansion valve for each of said evaporators, a return pipe for leading gaseous refrigerant from the evaporators

to said condenser, a jet injector in the return line adjacent the condenser, a pump in the connection between the receiver and the evaporators and arranged to force liquid refrigerant from 5 said receiver through a nozzle in said jet and thereby increase the speed of refrigerant in the condenser, a motor for driving said pump, and control means actuated by pressure in said return pipe for controlling the operation of said motor, 10 said control means operating independently in respect to the operation of said first control.

8. In a system of the character described, a main refrigerated evaporator, a condenser in contact with said evaporator and adapted to receive 15 gaseous refrigerant from a plurality of auxiliary evaporators, a receiver connected to said condenser adapted to supply liquid refrigerant to said auxiliary evaporators, and means for superimposing a spray of liquid refrigerant from the 20 receiver upon said gaseous refrigerant entering said condenser for accelerating heat transfer from said auxiliary evaporator to said main evaporator.

9. In a refrigerating system, a refrigerated 25 chamber, an auxiliary condenser in heat exchange relation to said chamber, a receiver associated with said condenser, a plurality of evaporators, an auxiliary receiver, a liquid line leading from said first receiver to said auxiliary receiver, a 30 pump between said first receiver and the auxiliary receiver, a second liquid line connecting the auxiliary receiver to said evaporators, and a return pipe leading from said last receiver and said evaporators to said condenser.

35 10. In a refrigerating system, a refrigerated chamber, an auxiliary condenser in heat exchange relation to said chamber, a receiver associated with said condenser, a plurality of evaporators,

an auxiliary receiver located at a point above the level of said evaporators, a liquid line leading from said first receiver to said auxiliary receiver, a pump connected into said liquid line, a second liquid line connecting the auxiliary receiver to 5 said evaporators, and a return pipe leading from said last receiver and said evaporators to said condenser.

11. In a refrigerating system, a refrigerated chamber, an auxiliary condenser in heat exchange 10 relation to said chamber, a receiver associated with said condenser, a plurality of evaporators, an auxiliary receiver located at a point above the level of said evaporators, a liquid line leading from said first receiver to said auxiliary receiver, a 15 pump between said first receiver and said liquid line, a second liquid line connecting the auxiliary receiver to said evaporators, a return pipe leading from said last receiver and said evaporators to said condenser and a check valve between said 20 last receiver and said return pipe.

12. In a system of the character described, a refrigerated chamber, an auxiliary condenser in heat exchange relation to said chamber, a receiver associated with said condenser, a plurality of 25 evaporators, an auxiliary receiver located at a point above the level of said evaporators, a liquid line having a pump therein and adapted to carry liquid refrigerant from said first receiver to said auxiliary receiver, a valve for controlling the level 30 of refrigerant in the auxiliary receiver, a second liquid line connecting said auxiliary receiver to said evaporators, a return pipe leading from said last receiver and said evaporators to said condenser, and a check valve between said last receiver and said return pipe.

SIEGFRIED RUPPRICHT.
